United States Patent Office.

JULES SEMELÉ, OF NEW YORK, N. Y., ASSIGNOR TO HIMSELF AND JOSEPH GARRUS, OF SAME PLACE.

Design No. 4,064, dated May 24, 1870.

DESIGN FOR A NEEDLE-CASE.

The Schedule referred to in these Letters Patent and making part of the same

To all whom it may concern:

Be it known that I, JULES SEMELÉ, of the city, county, and State of New York, have invented a new Design for a Needle-Case; and I do hereby declare that the following is a full, clear, and exact description of the same, reference being had to the accompanying drawing forming part of this specification, in which—

Figure 1 is a side view of the case.

Figure 2 is a view of the edge of the same, which is undermost in fig. 1.

Figure 3 is a view of the edge, which is uppermost in fig. 1.

Figure 4 is a longitudinal section.

Similar letters of reference indicate corresponding parts in the several figures.

My design represents the pod of a pea or bean, which is hollow, as shown at *a* in fig. 4, for the reception of the needles, and the stalk of which, of a configuration shown in the several figures, forms a stopple, which is removable from the pod portion *A* for the insertion and removal of the needles.

What I claim, and desire to secure by Letters Patent, is—

The design and configuration of the needle-case herein described, and represented in the accompanying drawing.

JULES SEMELÉ.

Witnesses:

FRED. HAYNES,
R. E. RABEAU.
